US0D1049085S

(12) **United States Design Patent** (10) **Patent No.:** **US D1,049,085 S**
(45) **Date of Patent:** **** Oct. 29, 2024**

(54) **ANTENNA**

(71) Applicant: **Shenzhen Antop Technology Co., Ltd.**,
Guangdong (CN)

(72) Inventor: **Ruidian Yang**, Guangdong (CN)

(73) Assignee: **SHENZHEN ANTOP
TECHNOLOGY CO. LTD.**,
Guangdong (CN)

(**) Term: **15 Years**

(21) Appl. No.: **29/882,403**

(22) Filed: **Jan. 13, 2023**

(30) **Foreign Application Priority Data**

Dec. 28, 2022 (CN) 202230866395.9

(51) **LOC (14) Cl.** **14-03**

(57) **CLAIM**

The ornamental design for an antenna as shown and described.

DESCRIPTION

FIG. 1 is a front elevational view of an antenna showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.

The broken lines in the drawings depict portions of the antenna that form no part of the claimed design.

1 Claim, 8 Drawing Sheets
